[57] **CLAIM**

The ornamental design for a cover for a cooking vessel with a steam vent, as shown and described.

DESCRIPTION

FIG. 1 is a top perspective view of a cover for a cooking vessel with a steam vent showing my new design;

FIG. 2 is a front elevational view, the rear elevational view being a mirror image thereof;

FIG. 3 is a top plan view thereof;

FIGS. 4, 5 and 6 are views similar to FIGS. 1, 2 and 3, but with said steam vent in a second position thereof;

FIG. 7 is a side elevational view thereof from the right of FIG. 2; and,

FIG. 8 is a side elevational view thereof from the left of FIG. 2.

The appearance of the underside is not claimed.
